DESIGN FOR A CLOTHES STICK

Paul J. Groeber, Springfield, Ohio

Application January 20, 1936, Serial No. 60,689

Term of patent 3½ years

To all whom it may concern:

Be it known that I, Paul J. Groeber, a citizen of the United States, residing at Springfield, in the county of Clark and State of Ohio, have invented a new, original, and ornamental Design for a Clothes Stick, of which the following is a specification, reference being had to the accompanying drawing, forming part thereof.

I claim:—

The ornamental design for a clothes stick as shown.

PAUL J. GROEBER.
